(57) **CLAIM**

The ornamental design for a pet fence, as shown and described.

DESCRIPTION

FIG. 1 is a first perspective view of a pet fence design showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion "9" in FIG. 1.

Any shading and cross-hatching are not features of the design but are utilized to illustrate the surface contours of the pet fence design in the drawings. The broken lines depict portions of the pet fence, and form no part of the claimed design.
